[57] CLAIM

The ornamental design for a bracket for supporting a
sprinkler head, substantially as shown and described.

DESCRIPTION

FIG. 1 is a perspective view of a bracket for supporting
a sprinkler head showing my new design;

FIG. 2 is a front view thereof;

FIG. 3 is a side view taken from the right of FIG. 2;

FIG. 4 is a side view taken from the left of FIG. 2;

FIG. 5 is a top view thereof;

FIG. 6 is a bottom view thereof.
